EX

No. 11,814

JUNE 8, 1880

UNITED STATES PATENT OFFICE.

GEORGE WILKINSON, OF PROVIDENCE, RHODE ISLAND, ASSIGNOR TO GORHAM MANUFACTURING COMPANY, OF SAME PLACE.

DESIGN FOR SPOON AND FORK.

SPECIFICATION forming part of Design No. 11,814, dated June 8, 1880.

Application filed February 9, 1880. Term of patent 7 years.

To all whom it may concern:

Be it known that I, GEORGE WILKINSON, of the city and county of Providence, and State of Rhode Island, have invented a new and original Design for the Handles of Spoons and Forks in Silver and Plated Wares, of which the following is a specification.

In the accompanying photograph, A represents a front view of the design, the outline of which is an essential feature. The upper portion at the point designated 1 is a shell-like decoration raised from the surface of the spoon, underneath which decoration is a curved line of beads. The section from 2 to 3 consists of a series of short raised lateral lines. At the point 4 is a narrow ornamental transverse band. The section designated 5 consists of a series of curved lines tapering as they approach the end of the handle.

B represents the reverse view of the design. The section marked 6 is a decoration representing the under surface of the shell. At the termination of the handle, at the point designated 7, the ornamentation is in the form of raised corrugations radiating fan-like from a common point.

The several features of ornamentation above described are to be substantially such as shown in the accompanying photographic illustration.

I claim as my invention—

The design for spoon and fork handles, consisting of the parts 1, 2, 3, 4, 5, 6, and 7, substantially as herein shown.

GEO. WILKINSON.
